United States Patent Office

Des. 212,523
Patented Oct. 29, 1968

212,523

BOTTLE

John W. Affleck, West Bridgetown, Nova Scotia, and Kenneth P. Jolly, Toronto, Ontario, Canada, assignors to Acadian Distillers Limited, Bridgetown, Nova Scotia, Canada, a corporation of Nova Scotia

Filed July 5, 1967, Ser. No. 7,718

Claims priority, application Canada Jan. 27, 1967

Term of patent 14 years

(Cl. D9—115)

FIG. 1 is an elevational view of a bottle embodying our new design;

FIG. 2 is a bottom plan view;

FIG. 3 is an elevational view taken at an angle of 45° to the left of FIG. 1; and

FIG. 4 is a top plan view thereof.

The sides opposite those seen in FIGS. 1 and 3 are the same in appearance as the sides shown.

We claim:

The ornamental design for a bottle, as shown and described.
